IGNITION DEVICE FOR GAS STOVES

Carl E. Methudy, St. Louis, Mo., assignor, by
mesne assignments, to The Cleveland Trust
Company, Cleveland, Ohio, a corporation of
Ohio

Application September 5, 1931, Serial No. 561,364

8 Claims. (Cl. 158—115)

This invention relates to ignition devices for gas stoves, and it consists of various novel features of construction and arrangement of parts for cooperation with the usual gas burners and pilot light device for improving the cooperation between these parts in conducting gas from the gas burners to the pilot light device and in directing the pressure wave of ignition from the pilot light device to the gas burners so as to ignite the gas passing from said burners; and it also consists in novel means for supporting the ignition device proper in a manner in which said ignition device will entirely, or to an extent, support the usual gas burners of the gas stove.

Objects of the invention are to provide an improved ignition device for gas burners for obtaining the results and cooperative actions above indicated in an effective manner and for improving the combustion of the gas conducted from the usual gas burners to the pilot light device; to provide a construction and arrangement whereby the necessity for an accurate or precise adjustment of the usual air valves is avoided; and to obtain all of the other advantages of the invention herein disclosed, reference being made to the accompanying drawings, in which—

Fig. 1 is a plan view, with parts in section, of the present invention.

Fig. 2 is a vertical sectional view of the ignition device and a portion of the gas burner supported thereby.

Fig. 3 is an end elevation of one of the tubes leading from the pilot light.

Fig. 4 is a view showing other variations in the construction of the tubes for conducting gas from the usual burners to the pilot light device and for conducting the ignition from the pilot light device to said burners.

Fig. 5 is a view showing one of the air valves in connection with the pipes leading to the gas burners.

Fig. 6 is an enlarged cross sectional view on the line 6—6 of Fig. 4.

The invention comprises a pilot light housing 1 having openings at its upper and lower end and provided at its lower end with lateral extensions 2. As shown, the extensions 2 project inwardly from integral connection with the lower end of the housing 1 and are seated upon a member 3 that is rigidly mounted in connection with the gas stove, so that the housing 1 is rigidly and immovably located. The extensions 2 are detachably secured to the support 3 by removable fasteners 4 passing through the support 3 and

the extensions 2 and clamping said parts together in rigid relationship.

A pilot light device 5 is in or adjacent to the open lower end of the housing 1 and is provided with a constant supply of gas through a tube 5 6 extending to communication with a gas manifold 7 and controlled by a valve 8 whereby the amount of gas passing to the pilot light device may be varied and controlled, as desired.

A top for the pilot light housing comprises 10 a disc 9 having therethrough a central hole 10 above the pilot light device and a series of spaced holes 11. These holes contribute to the proper combustion of the gas entering the housing and permit the burned gases to escape from 15 the housing. The disc 9 is secured to the housing by any appropriate means as by an annular flange 12 in connection with the disc 9 and having telescoping engagement with the upper end of the housing 1 (Fig. 2).

A tubular socket 13 opens from one side of the housing 1 opposite a vent opening 14 in the wall of said housing.

This pilot light housing is supported at a distance from the usual gas burner or cluster of 25 burners 15 and at a distance from another burner 16 specially provided at a distance from the pilot light device and also at a distance from the usual oven burner (not shown) of the gas stove. A tube 17 conducts gas to the burner 16 which is 30 within a burner housing 18. A tube 19 has one end opening into the housing 18 and the opposite end opening into the socket tube 13. It is now clear that gas passing through the tube 17 into the housing 18 will be conducted through the tube 35 19 to the pilot light housing 1 and ignited in said housing 1. This will ignite the gas in the tube 19 and will also ignite the gas in the housing 18 and at the burner 16. Gas is conducted through the pipe 17 to the burner tip 16 constantly during 40 the time that gas is conducted to the oven burner substantially in the manner disclosed in my co-pending application, Serial No. 406,218. The connections for controlling the supply of gas to the usual oven burner and consequently to the burner 45 16 are fully disclosed in my said copending application and are not specifically claimed in this invention beyond the extent shown in the annexed drawings. A tube 20 from the burner device 18 is designed and adapted to receive gas 50 from the usual oven burner (not shown) in the manner disclosed in my said copending application. When the gas at the burner 16 is ignited, the flame of said ignition ignites the gas in the tube 20, causing a flame of ignition to pass to the 55

usual oven burner and ignite the gas passing from the ports of said oven burner in the manner described in my said copending application.

The tube 19 is formed with a number of inwardly extended rifles 21 and the tube 20 is formed with similar rifles 22. These rifles are preferably formed in connection with opposite walls of the tubes 19 and 20 and serve to cause a better mixture of air and gas and to improve the combustion and otherwise increase the efficiency of the action of the device in igniting the oven burner.

Gas is supplied to the burners 15 from the manifold 7 through pipes 23. Valve devices 24 control the passage of gas from the manifold 7 into the pipes 23. Each pipe 23 is formed with an enlargement or bell 25 receiving the gas from the valves 24 and having air inlet openings 26 (Fig. 5). A rotary valve 27 is mounted in connection with each air inlet device 26 and is adjustable in a familiar manner to vary and regulate and control the admission of air into the pipes 23 and the mixture of the air with the gas passing to the burners 15.

In gas stoves of ordinary construction heretofore in use, somewhat accurate and precise adjustment of the valves 27 has been necessary in order to obtain best results. The present invention in addition to functioning as automatic igniters for the gas burners also serves to hold the gas burners in proper relationship to the ignition device, to improve the mixture of air and gas passing from the gas burners to the ignition device and thus making it unnecessary to manipulate and adjust the valve 27 in order to obtain proper mixture of air and gas to enable the present invention to function as an automatic igniter. Certain ignition devices heretofore in use in order to function most efficiently have required accurate adjustment of the air admission valves 27.

To the extent already described, all species of the invention herein disclosed are alike and the different species will now be described.

In the embodiment of the invention shown in Fig. 1, the housing 1 is rigid with and opens into tubes 28, 29, 30, and 31. These tubes extend toward the respective burners 15 and at their outer ends have arms 32 projecting under adjacent portions of the respective burners 15. Lugs 33 on the respective burners 15 engage in holes 34 in the projections 32. Since the ignition device comprising the housing 1 and its attachments are rigidly supported, the burners 15 are attached to the ignition device in a manner preventing relative movement or displacement of the burners and the ignition device.

One of the side walls of each of the burners 15 is formed with a gas outlet opening 35, which may be directed at any desired angle of inclination with respect to the adjacent end of the cooperating ignition tube, as will be understood by reference to Fig. 1 showing gas flames at the respective gas outlet openings 35.

The tube 28 has a flared or enlarged portion 36 at its end adjacent to the burner 15 so as to admit air freely to said tube for mixture with the gas passing into the tube from the port 35. A spiral element 37, which may comprise a wire shaped in spiral form, is supported within the tube 28 in a manner in which the coils of said spiral element are spaced apart and form a spiral channel communicating with the opening or passage through said spiral member. This spiral member breaks and agitates the body of gas passing through the tube 28 so as to obtain a proper

mixture of air with the gas and provide for better combustion. When gas is admitted to the burner 15 and passes from the opening 35 into and through the tube 28 and enters the housing 1, said gas is ignited, causing an ignition flame to pass through the tube 28 to the burner 15 and ignite the gas at the port 35 and thereby ignite the gas passing from the usual burner ports 38.

The tube 29 has a flared or enlarged portion 39 adjacent to the burner 15 and is formed on its inside with two zigzag ribs 40 extending inwardly from opposite walls of said tube 29. These ribs 40 serve to obtain a better mixture of air and gas and to improve the performance of the device. It will be understood that the use of the devices 37 and 40 is optional.

The tube 30 is formed with a flared or enlarged portion 41 adjacent to the burner 15. The tube 30 does not include any mixing members but has a comparatively smooth inner surface. The flared or enlarged portion 41 is arranged adjacent to the gas outlet 35, so that gas passing from said outlet will enter and pass through said tube 30 to the pilot light housing. At the pilot light housing gas is ignited and a pressure wave is caused to return to the burner 15 and ignite the gas passing from the port 35 and from the ports 38.

The tube 31 is of zigzag construction and has on its outer end a flared or enlarged portion 42 receiving gas from the adjacent port 35 and causing the gas to pass through the tube 31 to the pilot light housing. The ignited gas in the tube 31 causes ignition of the gas at the ports 35 and 38. The zigzag construction of the tube 31 dispenses with the need for using mixing members within the tube.

In the arrangement shown in Fig. 2, a tube 43 opening from the pilot light housing 1 has on its outer end a flared or enlarged portion 44 adjacent a burner 45. The burner 45 has in its top gas outlet openings 46 and in one side wall has a gas outlet opening 47 arranged to discharge gas into the enlargement 44 of the tube 43. The enlargement 44 has on its inside a partition 48 below which the gas from the port 47 passes into the tube 43. A number of projections 49 are formed within the tube 43 in order to create an improved mixture of air and gas and improve the performance of the device. Gas passing through the tube 43 to the pilot light housing 1 is there ignited and a flame of ignition passes through said tube 43 toward the burner 45. The inclined upper wall 50 of the partition 48 directs the flame of ignition upwardly toward the top of the burner 45 so that the gas passing from the ports 46 will be ignited. This is an embodiment of means whereby I am enabled to locate the ends of the tubes extending from the pilot light housing in a relationship in which the upper sides of said tubes are not above the burners 15 or 45. By this construction, I am enabled to obtain many or all of the advantages that are obtained by that construction and arrangement in which the ends of the tubes from the pilot light housing discharge above the upper surfaces of the burners.

In the variation of the invention shown in Figs. 4 and 6, tubes 51 extend and open from the pilot light housing 1, and have on their outer ends flared or enlarged portions 52 arranged in such a relationship to the ports 35 that gas discharged from said ports 35 will enter said tubes 51. The gas passes through the tubes 51 into the pilot light housing 1 and is there ignited, causing a

flame of ignition to pass through said tubes 51 to the respective burners 15. The gas passing from the ports 35 and 38 is thereby ignited.

The ends of the tubes 51 have projections 53 extending under and engaging the burners 15 in the same manner as the extensions 32 engage said burners. The housing 1 is rigidly supported in any appropriate manner, as by a support similar to the support 3.

0 The tubes 51 have ruffles 54 along the inner walls thereof. These ruffles cause agitation of the gas passing through the tubes in a manner to obtain better mixture of air and gas, so that better and more perfect combustion is obtained.

5 It is clear that in both embodiments of the invention shown, the ignition device comprising the pilot light housing and its associated parts is rigidly supported and has connection with the regular gas burners of the stove, so that said gas 0 burners are rigidly supported with respect to the ignition device. Further, the connection between the ignition device and the regular gas burners constitutes a guide for the workmen in assembling the parts, it being apparent that the parts are 5 not in proper relationship until the lugs 33 of the gas burners are engaged in the holes 34 of the ignition device. This prevents the ignition device and the burners from turning relatively and also prevents said parts from substantial 10 turnable displacement. The novel features for improving the mixture of air and gas cooperate satisfactorily with the remaining features of the invention.

I am aware that the construction and arrangement may be varied otherwise than as specifically shown and described without departure from the nature and principle of the invention. I do not restrict myself in any unessential particulars but in the appended claims define the invention as broadly as the scope of equivalent limits will permit.

I claim:

1. In a gas stove, a burner having gas outlet openings, a pilot light housing spaced from said burner, a constantly burning pilot light device operating into said housing, a flash tube having a straight line of ignition passage from end to end opening from said housing and having one end opening adjacent to said burner in position to receive gas from one of said gas outlet openings and to conduct the gas to said housing for ignition by said pilot light device and for conducting the flame of ignition of the gas toward said burner, means cooperating with the wall of said tube adjacent said burner for directing the flame of ignition from said tube toward said burner, and means for holding said burner and tube in proper cooperative relationship.

2. In a gas stove, a burner having gas outlet openings, a pilot light housing spaced from said burner, a constantly burning pilot light device operating into said housing, a flash tube having a straight line of ignition passage from end to end opening from said housing and having a flaring end opening adjacent to said burner in position to receive gas from one of said gas outlet openings and to conduct the gas to said housing for ignition by said pilot light device and for conducting the flame of ignition of the gas toward said burner, means cooperating with the wall of said tube adjacent said burner for directing the flame of ignition from said tube toward said gas outlet openings in said burner.

and means for holding said burner and tube in proper cooperative relationship.

3. In a gas stove, a burner having gas outlet openings, a pilot light housing spaced from said burner, a constantly burning pilot light device operating into said housing, a flash tube having a straight line of ignition passage from end to end opening from said housing and having one end opening adjacent to said burner in position to receive gas from one of said gas outlet openings and to conduct the gas to said housing for ignition by said pilot light device and for conducting the flame of ignition of the gas toward said burner, and a deflector other than the wall of said tube and adjacent to said burner for deflecting the flame of ignition properly to ignite gas issuing from said outlet openings.

4. In a gas stove, a burner having gas outlet openings, a pilot light housing spaced from said burner, a constantly burning pilot light device operating into said housing, a flash tube having a straight line of ignition passage from end to end opening from said housing and having one end opening adjacent to said burner in position to receive gas from one of said outlet openings and to conduct the gas to said housing for ignition by said pilot light device and for conducting the flame of ignition of the gas toward said burner, and a device within the flared end of said tube and spaced from the upper wall thereof for deflecting the flame of ignition toward certain of said outlet openings.

5. In a gas stove, a burner having gas outlet openings, a pilot light housing spaced from said burner, a constantly burning pilot light device operating into said housing, a flash tube having a straight line of ignition passage from end to end opening from said housing and having one end opening adjacent to said burner in position to receive gas from one of said gas outlet openings and to conduct the gas to said housing for ignition by said pilot light device and for conducting the flame of ignition of the gas toward said burner, means in said tube for effecting mixture of air and gas passing through said tube to said pilot light housing, means cooperating with the wall of said tube adjacent said burner for directing the flame of ignition from said tube toward said gas outlet openings in said burner, and means for holding said burner and tube in proper cooperative relationship.

6. In combination, a gas burner having gas outlets at one elevation and a gas outlet port at a different elevation, a pilot light device spaced from said burner, a flash tube having one end adjacent to said pilot light device and its opposite end terminating adjacent said burner for receiving gas from said port and to conduct the same toward said pilot light device for ignition and for conducting the flame of the ignited gas back toward said burner, said last mentioned end having at least a substantial portion thereof terminating below the elevation of said gas outlets and at the level of said port, and a baffle means within said last mentioned end for directing the flame of ignition upwardly toward said gas outlets to ignite gas issuing therefrom.

7. In combination, a gas burner having gas outlets at one elevation and a gas outlet port at a different elevation, a pilot light device spaced from said burner, a flash tube having one end adjacent to said pilot light device and its opposite end terminating adjacent said burner for receiving gas from said port and to

conduct the same toward said pilot light device for ignition and for conducting the flame of the ignited gas back toward said burner, said last mentioned end having at least a substantial portion thereof terminating below the elevation of said gas outlets and at the level of said port, and a baffle means within said last mentioned end for directing the flame of ignition upwardly toward said gas outlets to ignite gas issuing therefrom, said baffle means comprising a horizontal partition element extending between the walls of said last mentioned end above the level of said port.

8. In a gas stove, a gas burner having outlet openings through the top thereof and having a gas port through one side thereof, a pilot light

10 housing spaced from said burner, a constantly burning pilot light device operating into said housing, a flash tube having a straight line of ignition passage from end to end opening from said housing and having one end adjacent to said gas port to receive and conduct gas from said port to said pilot light housing for ignition by said pilot light device and for conducting the flame of ignition of the gas toward said burner, means within said tube and cooperating with the wall thereof for directing the flame of ignition from said tube toward said outlet openings, and means for holding said burner and tube in proper cooperative relationship.
